UNITED STATES PATENT OFFICE

LOUIS J. LOEFFLER, OF STAPLETON, NEW YORK.

DESIGN FOR A DESK STAND FOR A HAND TELEPHONE

Application filed July 26, 1930. Serial No. 36,488. Term of patent 14 years.

To all whom it may concern:

Be it known that I, LOUIS J. LOEFFLER, a citizen of the United States, residing at Stapleton, in the county of Richmond and State of New York, have invented a new, original, and ornamental Design for Desk Stand for a Hand Telephone, of which the following is a specification, reference being had to the accompanying drawing, forming part thereof, in which:—

Fig. 1 represents a top view of a desk stand for a hand telephone embodying this design.

Fig. 2 is a side elevation thereof.

Fig. 3 is a rear view of the same.

I claim:

The ornamental design for a desk stand for a hand telephone as shown.

LOUIS J. LOEFFLER.
